UNITED STATES PATENT OFFICE.

SVANTE R. W. M. BAGER, OF SOUTH MILWAUKEE, WISCONSIN, ASSIGNOR TO BUCYRUS COMPANY, OF SOUTH MILWAUKEE, WISCONSIN, A CORPORATION OF WISCONSIN.

EXCAVATOR SUPPORTING FRAME AND TRACTION MEANS THEREFOR.

Application filed February 7, 1921. Serial No. 443,106.

To all whom it may concern:

Be it known that I, SVANTE R. W. M. BAGER, a citizen of the United States, and a resident of South Milwaukee, in the county of Milwaukee and State of Wisconsin, have invented certain new and useful Improvements in Excavator Supporting Frames and Traction Means Therefor; and I do hereby declare that the following is a full, clear, and exact description thereof.

My invention pertains to the general class of excavators and digging machinery and relates particularly to new and useful improvements in the manner of constructing and mounting different parts of such machinery.

While the general construction of excavating machinery for different purposes is more or less similar, there are various minor differences which have heretofore rendered it impractical to build a single machine for all purposes, although it has been more or less possible to rebuild minor parts as where it is desirable to convert a railway machine to a caterpillar driven machine, or one with ordinary ground-engaging wheels.

It is therefore a fundamental object of this invention to provide a main or supporting frame of such construction that it may be readily accommodated for use with various types of traction mechanism. In other words the simple changing of the traction mounting means will selectively convert the frame from one for use with an excavator adapted to operate on railway tracks to one driven by caterpillar belts, or equipped with conventional ground-engaging wheels.

It is furthermore an object of this invention to provide a ground traction mechanism for machinery of this character with such means that its steering wheels may be selectively placed close to the main supporting frame to considerably reduce the overall width of the machine for transportation purposes, or space such wheels from the frame to allow for proper steering operations.

It is further an object of the invention to provide a machine having traction means of this character in which the steering axle is usually tiltable, with means for rigidly fixing the main supporting frame and axle

together when the excavating or other machinery carried by the former is in operation.

It is likewise an object of this invention to provide the ground-engaging wheels of the traction mechanism with relatively wide tread surfaces, the outer edges of which extend beyond the outer ends of the wheel hubs and the adjacent ends of the axles for protective purposes.

With the foregoing important objects in view the invention resides in the novel features of construction, combination and arrangement of parts which will be herein-after more particularly described and claimed.

In the accompanying drawings—

Figure 1 represents a plan view of one of the standardized convertible main supporting frames of an excavator or similar machine and provided with ground wheel traction mechanism;

Figure 2 is a side elevational view, partly in section, of the structure shown in Figure 1;

Figure 3 is a transverse sectional view on the plane of the line 3—3 of Figure 1;

Figure 4 is a similar view, the illustrated wheel being positioned in its inoperative position as when arranged for transportation;

Figure 5 is a detail transverse sectional view through the standardized main supporting frame showing a jack-arm mounted thereon, and

Figure 6 is a view somewhat similar to Figure 5 showing the use of a caterpillar wheel carrying bracket mounted thereon.

Referring more particularly to the drawings, it will be seen that the standardized frame which can be converted for use in connection with various types of excavator or similar machinery traction mechanisms includes a pair of longitudinal side bars or sills 1 spaced apart a suitable distance and connected at their ends by a pair of end bars or sills 2, thus forming a rectangular frame. The middle portions of this frame are braced by two pairs of intermediate transverse sills or bars 3 and 4, all of which bars as well as the side and end bars are preferably of heavy I-beam construction. A pair of side cover plates 5 are disposed on and extend inwardly from the top flanges of the side bars 1, and these plates are riv-

eted to said side bars and the transverse or cross-bars, while a transverse cover plate 6 is disposed on each pair of the intermediate transverse bars 3 and 4 and riveted to their flanges.

A rack and track member preferably in the form of a single annular casting 7 is mounted on the several cover-plates, it resting particularly on the cover plates 6 supported by the transverse bars 3 and 4, and overlapping the side cover plates 5 and the intermediate portions of the side bars 1 (see Figure 1). The casting 7 is riveted as at 8 to the several cover plates and is thus retained in proper relation to the different elements of the main frame. The rack and track member includes inwardly extending radial arms 9 which merge into a central bearing sleeve 10, and the portions of these 20 arms adjacent their connection with the annular portion of the casting 7 are transversely widened to provide attaching plates 11 which overlie the transverse bars 3. The central bearing sleeve 10 receives a vertical 25 propulsion shaft 12 which is connected with the machinery drive mechanism (not shown), and the upper end of said sleeve also forms a trunnion for the revolving frame (also not shown) which rests on the 30 track portion of the casting 7.

The rack and track casting is further secured to the other parts of the frame by pairs of tie bolts 13 which are passed through said attaching plates 11, each pair 35 of said bolts straddling a respective transverse bar 3 and being connected at their lower ends by a suitable tie plate member. These bolts 13 obviously take up the tilting 40 stresses involved in the operation of the heavy machinery mounted on the main supporting frame and relieve such stresses from the various rivets, including the rivets 8. Increased rigidity of the front end of the main supporting frame is obtained by 45 mounting a combined bearing and bracing casting 14 between the front end bar 2 and the forward transverse bar 4 and securing the same midway of the ends of the latter. This casting 14 obviously aids in evenly distributing 50 stresses imparted to the draw head 15.

The foregoing described main supporting frame including the various side bars and rack and track member is standard for different types of traction mechanisms, and is readily convertible from one to the other. The tie bolts 13 play an important part in the use of this frame, it being obvious that under all conditions they secure the different 60 parts rigidly together, they being aided in this by the tie plate members by which their lower ends are connected together, which tie plate members bear against the lower flanges of the transverse bars 3. When the main 65 supporting frame is arranged for use with

ground wheel traction mechanism as illustrated in Figures 1 and 2, the tie plate members are merely in the form of flat plates 16, but on the other hand if a type of traction mechanism is employed which requires 70 the use of a restraining means including the jack and jack-arm, as disclosed in the co-pending application Serial Number 443,069, filed February 7, 1921, a jack-arm sill 16' forms the tie plate member. As shown in 75 Figure 5 and in said co-pending application, this sill 16' connects each longitudinally arranged pair of tie bolts and is engaged against the under sides of the bars 3. Furthermore when the main supporting frame is to be propelled by a caterpillar traction mechanism, as illustrated in the co-pending application Serial Number 443,164, filed February 7, 1921, the tie plate member is provided by the inner end portion 16'' of a 80 wheel supporting cantilever bracket 17 (see Figure 6). Thus it will be seen that while the main supporting frame is readily convertible, its rigidity is maintained irrespective of the character of the traction mechanism employed therewith.

In converting the main supporting frame to its different uses, it may also be necessary to change the front and rear axles, but such would involve merely common practice and 90 would be made regardless of the construction of the frame. For instance in the present application wherein is particularly shown the frame in use with ground-engaging wheels, the rear axle 18 is journally mounted in bearings 19 fixed to the side bars 1 at their rear ends. Intermediate the ends of the axle is disposed a beveled gear 20 which is meshed with a beveled pinion 21, the latter in turn being gear connected with a similar beveled pinion 22 on the lower end of the main propulsion shaft 12. Wheels 23 are mounted on the outer ends of the axle 18 and are located relatively close to the side bars of the frame.

As is usual in structures of this character the front axle 24 is tiltable to compensate for various irregularities in the surface over which the machine passes, and this axle is supported in its center from the combination 115 casting 14 hereinbefore described. This casting includes a bearing sleeve 25 which receives a vertical shaft or king-pin 26, the latter having an enlarged bifurcated head 27 on its lower end, the ears or furcations of 120 which straddle the axle 24 and are pivotally connected therewith by a pin 28. The portion of the head of the king-pin 26 between the ears thereof is slightly convex as at 29, and the axle 24 bears against this portion 125 which thus forms a rocking surface. Obviously this mounting of the axle permits tilting as well as steering movements to be effected, the latter being carried out by means of suitable steering mechanism not shown. 130

The opposite ends of the axle 24 are provided with spindle portions 30 which are of considerably greater length than the length of the hubs 31 of the wheels 32. The wheels 5 are retained on the axle ends by means of retaining collars 33 preferably disposed in annular grooves cut in the extreme outer end portions of the spindles 30. When the machine is to be used, the wheels 32 are located 10 at their outermost limits, or in other words the outer ends of the hubs 31 about the retaining collars 33, it being necessary to have the relative distance between the wheels and the space between the same and the adjacent side bars of the frame as great 15 as possible so that effective steering of the front axle 24 may be carried out. Under such conditions said wheels 32 are retained at their outer limits by interposing spacing 20 collars 34 between the inner ends of the hubs 31 and the inner ends of the spindles 30.

On the other hand when the parts of the machine are arranged for shipment on a railway flat car for instance, it is necessary 25 to reduce the overall width of the machine as much as possible. Therefore the spacing collars 34 are removed from their normal positions at the inner ends of the hubs 31 and interposed between the outer ends of the 30 hubs and the retaining collars 33. This disposes the wheels 32 relatively close to the side bars of the main supporting frame and reduces the distance between such wheels as is obvious from an examination of Figure 4. 35 The wheels 23 and 32 have relatively wide tread surfaces inasmuch as they are designed to support the weight of heavy machinery and to oftentimes move the same over rather soft ground. In the preferred embodiment 40 of these wheels, as clearly shown in Figures 3 and 4, the hubs thereof are connected with the tread surfaces by a solid web extending from the inner edge of such tread surfaces. Thus the outer edges of the tread surfaces 45 are disposed a considerable distance beyond the outer ends of the hubs, and when the wheels are in use, beyond the outer ends of the axles, thereby effectively protecting these parts against striking any obstructions 50 which may be encountered during the movement of the machine.

By reason of the hereinbefore described connection between the front axle and the main supporting frame, the former has a 55 considerable degree of tilting movement. However, when the machine is halted for operation of its excavating or other carried mechanism, it is desirable to hold the main supporting frame against movement with 60 respect to the axle 24, and to this end I provide means insertable between the axle and the superposed portion of the frame which is variable with respect to its effective width so as to properly engage the opposed portions 65 of the frame and axle in the various

relative positions which they may assume upon discontinuing propulsion of the machine.

This means consists of a metallic wedge structure, the axle 24 beneath each side bar 70 1 being accommodated to receive the same by the provision of a longitudinally channeled boss 35. In view of the degree of relative movement which may occur between the axle ends and the frame side bars, 75 the provision of a wedge having sufficient variation of height to compensate for this movement and of sufficiently slight pitch to insure its frictional retention in place, would entail such length to the wedge as to 80 render its manipulation rather inconvenient. Therefore a series of wedge sections 36 is provided, the same being progressively increased in height and affording continuations of a common pitch face, and thereby 85 constituting a wedge unit of sufficient length to compensate for the range of relative movement between each end portion of the axle and the corresponding frame bars.

These wedge units 36 are carried in trays 90 37 secured at the sides of the main supporting frame, hence when the machine is halted for operation of its main mechanism, the operator may select the necessary wedge unit section and place it in the channel 36, 95 it being driven home to make a rigid connection. It is to be noted that the faces of the bosses 35 on each side of the channels thereof are quite wide, in the present instance extending outwardly of the edges of 100 the lower flanges of the frame side bars, whereby it is possible in emergency to use wooden wedge members which would necessarily be of greater width than the channels which normally receive the metallic wedge 105 sections.

While I have shown and described a preferred embodiment of my invention, it will be understood that various changes and modifications of structure may be employed 110 to meet differing conditions of use and manufacture without departing in any manner from the spirit of my invention.

I claim:

1. A supporting frame for heavy portable machinery comprising a pair of side bars, a plurality of transverse connecting bars secured to the side bars, a superstructure track mounted on certain of said bars and connected with the same, said track having a central opening, radial arms extending inwardly from the track, a central bearing sleeve having said arms secured thereto and supported thereby, tie bolts extended through said arms adjacent said track and engaged with certain of said transverse bars, and tie-plate members disposed on the tie-bolts beneath the last mentioned transverse bars whereby said track, last mentioned bars and tie plates are bound rigidly together. 130

2. A supporting frame for heavy portable machinery comprising a pair of side bars, a pair of end bars connecting the side bars, a pair of spaced intermediately disposed transverse bars connecting the said side bars, a substantially annular superstructure track mounted on the side and intermediate bars and secured thereto, substantially radially disposed attaching plate portions projecting from the track, a pair of tie bolts extending through each of said attaching plate portions, the bolts of each pair straddling one or the other of said transverse bars, and tie plate members disposed on the bolts beneath the last mentioned transverse bars whereby said track, last mentioned bars and tie plate members are bound rigidly together.

3. A convertible supporting frame for heavy portable machinery comprising a pair of longitudinal bars, a pair of transverse bars connecting said longitudinal bars, axles mounted on said frame adapted to selectively receive any of a plurality of types of traction mechanisms, a superstructure track comprising a rigid unit mounted upon said longitudinal and transverse bars, and a plurality of connections between said unit and each transverse bar to bind said bars rigidly to said unit and thus increase the rigidity of said frame, said connections including tie-bolts embracing said transverse bars and adapted to selectively receive and secure beneath said bars tie-plates, roller supporting brackets or jack-arm en-

35 gaging sills.

4. A convertible supporting frame for heavy portable machinery comprising a pair of longitudinal bars, a pair of transverse bars connecting said longitudinal bars, a superstructure track comprising a rigid unit mounted upon said longitudinal and transverse bars, and a plurality of connections between said unit and said transverse bars to bind said bars rigidly to said unit and thus increase the rigidity of said frame, said connections comprising sets of tie-bolts extending downwardly from said unit adjacent said transverse bars, and replaceable means connecting the lower ends of the 50 tie-bolts of a set and bound thereby beneath said transverse bars.

5. In heavy portable machinery for excavating, loading and the like, the combination of a pair of longitudinal bars, means including a pair of transverse bars connecting said longitudinal bars to form a substantially rectangular frame, a superstructure track comprising a rigid unit mounted upon said longitudinal and transverse bars, sets of tie-bolts connected with said unit and extending downwardly therefrom adjacent certain of said bars, and means connecting the tie-bolts of each set and bound thereby beneath said adjacent bars for binding said bars rigidly to said unit whereby

the rigidity of said unit is utilized to increase the rigidity of said frame.

6. In heavy portable machinery for excavating, loading and the like, the combination of a pair of longitudinal sills, means including a pair of transverse bars connecting said sills to form a substantially rectangular frame, a rigid member constituting a superstructure track carried by said frame, and a plurality of rigid connections between said member and each of said bars to increase the rigidity of said frame, each of said connections extending through said member and embracing one of said bars to bind said bars rigidly to said member.

7. In heavy portable machinery for excavating, loading and the like, the combination of a frame comprising a pair of longitudinal bars and a pair of transverse bars connected to said longitudinal bars, a circular superstructure track mounted on said longitudinal bars and transverse bars, said track comprising a casting having inwardly extending radial arms formed integral therewith, a pair of tie-bolts extending through each arm and embracing one of said transverse bars, and means connecting the tie-bolts of each pair and bound thereby beneath said transverse bar for binding said bars rigidly to said track whereby the rigidity of said track is utilized to increase the rigidity of said frame.

8. In a machine of the character described, the combination of two pairs of bars connected to form a rectangular frame, a rigid unit mounted on said bars and comprising a circular track having a central hub portion integral therewith, and rigid connections between said unit and the bars of one pair whereby the rigidity of said unit is utilized to increase the rigidity of said frame.

9. In a machine of the character described, the combination of a base frame, a rigid unit mounted on said frame, said unit comprising a circular track portion adapted to support a revolving frame and a central hub portion adapted to receive a vertical propulsion shaft driven from the revolving frame, and connections within the periphery of said track for securing said unit to said base frame.

10. In a machine of the type in which a revolving head frame is employed, the combination of a rigid unit having a circular track portion for supporting the frame and a central hub portion integral with said track, a vertical propulsion shaft journaled in said hub portion, and driven from the frame, a base frame for supporting said unit, and traction means on said base frame driven by said shaft.

11. In a machine of the character described the combination of two pairs of

bars connected to form a rectangular frame, a circular track mounted thereon and providing a support for a revolving frame, a central shaft receiving bearing supported by said track and connected therewith to form a rigid unit, and means for binding said track to said bars to thereby utilize the rigidity of said track to increase the rigidity of said frame.

12. In a machine having a revolving frame, the combination of a base frame, traction means supporting said base frame,

a rigid circular track secured to and strengthening said base frame and constituting a support for the revolving frame, a vertical shaft extending from the revolving frame for driving said traction means, and a central bearing for said shaft rigidly connected with and supported by said track.

In testimony that I claim the foregoing I have hereunto set my hand at Memphis, in the county of Shelby and State of Tennessee.

SVANTE R. W. M. BAGER.
